(57) **CLAIM**

Having described my invention, I claim the ornamental design for a leaner seat with rod back, as shown and described.

DESCRIPTION

FIG. 1 is a top environmental view of a leaner seat with rod back.

FIG. 2 is a breakaway side of a leaner seat with rod back.

FIG. 3 is an enlarged top view of a leaner seat with rod back.

FIG. 4 is an enlarged front view of a leaner seat with rod back; and,

FIG. 5 is a side view of a leaner seat with rod back with a fishing rod shown in dotted lines in on of the holders of the seat back.

The broken lines are for illustrative purposes only and form no part of the claimed design.
